UNITED STATES PATENT OFFICE.

GEORGE W. GOMBER, OF CONYNGHAM, PENNSYLVANIA, ASSIGNOR TO A. W. DRAKE MANUFACTURING COMPANY, OF HAZLETON, PENNSYLVANIA, A CORPORATION OF PENNSYLVANIA.

WHEELED TOY.

Application filed September 22, 1921. Serial No. 502,342.

To all whom it may concern:

Be it known that I, GEORGE W. GOMBER, a citizen of the United States, residing at Conyngham, in the county of Luzerne and

5 State of Pennsylvania, have invented a new and useful Wheeled Toy, of which the following is a specification.

This invention relates to toys, and particularly to that class known as wheeled 10 toys wherein the device is adapted to be drawn along the ground to cause the rotation of bearing wheels and resulting in certain actuation of a figure or figures, connected thereto, in simulation of the natural 15 motions of said figures.

The object is to provide certain strengthening means for such toys consisting principally in the provision of a main frame therefor, which may be formed of a single 20 length of wire, so bent and shaped as to provide bearings for the front and rear axles, and forwardly of the front axle a fender-shaped portion having means for the attachment of a drawing cord, the balance 25 of the structure including the wheels and the figures, together with the manner of mounting and operating the same, being substantially the same as shown, described and claimed in the co-pending application, 30 filed by me, of even date herewith, Serial No. 502,341, filed September 22, 1921.

A full and complete understanding of the invention may be obtained from a consideration of the following detailed description 35 taken in connection with the accompanying drawings forming a part of this specification; it being understood that while the drawings show practical forms of the invention, the latter is not confined to strict 40 conformity therewith, but may be changed and modified so long as such changes and modifications mark no material departure from the salient features of the invention, as specifically pointed out in the appended 45 claims.

In the drawings, in which similar reference characters designate corresponding parts throughout the several figures:

Figure 1 is a side elevation of one form 50 of the invention showing three figures to be actuated thereby, in the form of horse-back riders.

Figure 2 is an inverted plan view of the same.

55 Figure 3 is a side elevation of a form of

the invention wherein a team of horses are shown drawing a cart or wagon.

Figure 4 is an inverted plan view of the same.

Figure 5 is a side elevation of a form 60 showing a team of horses in connection with a sulky and having a driver thereon.

Figure 6 is an inverted plan view of the same.

Referring to the drawings, there is illustrated in Figures 1 and 2, three figures 1 of running horses having riders or jockeys mounted on their backs, and the said horses and riders may be formed from a single piece of stout thin wood or beaver board 70 or other wood substitute suitably painted or decorated to represent the desired features, and the same may have similar outlines, though preferably painted or decorated differently to enhance the naturalness 75 thereof.

Each horse is provided with a forwardly extending stiff wire standard 2 rigidly secured thereto and located near the front legs thereof, reaching forwardly and downwardly with a lateral offset 3 extending beneath the legs of the horse and terminating in a transverse bearing sleeve 4 in the form of a coil, all of said sleeves being in horizontal alinement for the reception of the 85 front axle 5 having front carrying wheels 6 rigidly mounted on its ends. The construction of standard as shown and described is not specifically claimed in this application, but is made the subject of 90 claims in my aforesaid co-pending application.

The rear axle 7 is provided at its ends with drive wheels 8, which are rigidly secured thereto so as to cause a rotation of 95 the axle when the device is drawn forwardly, and the said axle is provided with intermediate bends constituting cranks 9 arranged at different angles with relation to each other, and adapted to have the lower 100 ends of pitmen 10 secured thereto, as by means of an eye formed of the wire composing the said pitmen, the latter preferably having angular bends 11 and having their upper forward ends pivotally connected to the rear portions of the figures 1, as by means of screws 12 traversing eyes 13 formed in the upper ends of the said pitmen.

One feature of novelty herein resides in 110

the main frame formed of a single length of stout wire bent intermediately of its ends to form side bars 14, joined at their front ends by the intermediate portion of said 5 length of wire and constituting a front fender or draw-bar 15 arranged in front of the front axle, and having a forwardly extending loop 16 for the purpose of attaching a string in order to draw the toy in a forward 10 direction, as will be readily understood. The side bars tie the two axles together and hold them in rigid relation to each other.

The rear ends of the side bars are farther 15 apart than the front ends thereof and terminate in bearing eyes 17 adapted to receive the rear axle and allow the same to freely rotate therein. The side bars are also bent into forward bearing eyes 18 for the reception 20 of the front axle, which also turns freely in the same.

It will be seen that when the device is drawn forwardly, the rear wheels will turn the rear axle in the bearings 17 of the 25 main frame, and that the several cranks will rise and fall at different times by reason of their angular relation, thus causing the several figures to partake of said rising and falling movement in a similar manner and 30 to give the appearance of a number of horses or other animals or figures in the act of racing, the front standards merely pivoting on the front axle to permit of such motions.

In Figures 3 and 4 of the drawings, substantially the same structure is employed for 35 mounting and actuating the horses or other animals and the same reference characters are applied thereto. The front wheels 6^a, however, in the form, are composed of a 40 length of wire bent to form a circular rim having an integral spoke 6^b, terminating at the center of the wheel in a hub-like coil 6^c, which firmly grasps the ends of the front axle 5 so as to prevent their detachment 45 from the same.

In like manner the rear axle 7 is provided at its terminals with wire wheels 8^a formed and attached in the same manner, and the pitmen 10 are somewhat longer than the first 50 described form and have the angular bends 11, and are attached to the figures 1 in the same manner, the distance between the front and rear wheels being considerably longer than that shown in Figures 1 and 2.

55 A wagon body 19, which may be formed of tin or beaver board, is mounted over the rear axle, and in the rear of the extended hind legs of the horses or figures 1, front and rear bolsters 20 and 21, respectively, 60 formed of wire, being employed to support said wagon body, the said wire being bent to form a transverse bar for attachment to the wagon body and having terminal legs provided with eyes, the eyes 20^a of the front 65 bolster being arranged to receive the side

bars 14 of the main frame and the rear bolster eyes 21^a receiving the rear axle 7, as clearly shown in Figure 4.

The main frame of this second form of the device is precisely the same as the first 70 described form, and is attached to the axles in the same manner, one difference in the structures residing in the fact that only two figures are shown, and also two cranks and pitmen. 75

In Figures 5 and 6 a pair of horses 1 are shown mounted in the same manner and adapted to be actuated in the same way. A sulky seat 22 is shown, however, having a driver 23 mounted thereon and held by a screw 24 fitting into a vertical slot 25 formed in a cleat 26 suitably secured to the seat 22, the said slot being open at its upper end so that the driver may be readily detached therefrom when desired. A seat support 85 formed of wire is used to hold the seat in position, the same being bent to form front legs 27 and rear legs 28 suitably secured to the main frame and the rear axle respectively, and carrying said seat as well as a foot rest or dash 29 which is suitably secured to said front legs 27.

From the foregoing it will be seen that a simple and cheaply manufactured frame for 90 toys of the class illustrated, described and claimed in the aforementioned co-pending application has been provided.

What is claimed is:—

1. A wheeled toy having a main horizontally disposed frame formed of a single 100 length of stiff wire and bent to provide a pair of spaced longitudinal side bars joined at their front ends by a transverse integral draw-bar provided with a forwardly extending loop, said side bars terminating at 105 their free, rear ends in bearing eyes for a rear axle, and having near the front draw-bar aligned bearing eyes for a front axle, said draw bar being arranged in front of and spaced from the front axle and serving 110 as a fender.

2. In a wheeled toy, the combination of the front axle, the rear axle, wheels for 115 said axles, the rear axle having a plurality of cranks, a plurality of figures, individual connections between each crank of the rear axle and the rear portion of each figure, individual connections between the front portion of each figure and the front axle, said 120 connections causing the figures to rise and fall, the front connections turning on the front axle, and a main frame connecting the said axles and tying them together, said main frame being independent of said connections and arranged outside the latter. 125

3. In a wheeled toy, the combination of the front axle, the rear axle, wheels for said axles, the rear axle having a plurality of cranks, a plurality of figures, individual connections between each crank of the rear axle 130

and the rear portion of each figure, individual connections between the front portion of each figure and the front axle, said connections causing the figures to rise and fall, 5 and constituting the sole supporting means for the figures and holding the latter out of contact with the axles, the front connections each comprising a standard terminating in a transversely arranged bearing, each bearing being fitted to turn on the front axle and arranged along the latter, and a main frame connecting the said axles and tying them together independently of the said individual connections and arranged outside 10 the latter, said frame having bearings for the said axles, the bearings for the front axle engaging the said first mentioned bearings.

4. In a wheeled toy, the combination of 20 the front axle, the rear axle, wheels for said axles, the rear axle having a plurality of cranks, a plurality of figures, individual connections between each crank of the rear axle and the rear portion of each figure, individual connections between the front portion 25 of each figure and the front axle, said connections causing the figures to rise and fall, the front connections turning on the front axle, a main frame connecting the said axles and tying them together, said main frame being independent of said connections and a vehicle body arranged in rear

of the figure and having supports connected respectively to the rear axle and the main frame.

35

5. A toy comprising a frame formed from a continuous piece of wire, two axles for said frame, one of said axles being in the form of a crank shaft, wheels on said axles, a figure, and standards at each end of the figure fixed thereto, one of said standards being pivoted to the crank of said crank shaft, and the other standard terminating in a bearing sleeve which embraces the other axle.

45

6. A toy comprising a frame formed of a continuous piece of wire, two axles for said frame, one of said axles being in the form of a crank shaft having a plurality of cranks, wheels on said axles, a plurality of figures spaced apart, and wire standards at each end of each figure and fixed thereto, the standards at one end of said figures being pivoted at one end to the separate cranks of said crank shaft, and the standards at the other end of said figures terminating in a transversely disposed bearing sleeve, said sleeves embracing the other axle and arranged therein in consecutive order between the sides of the frame.

55

In testimony that I claim the foregoing as my own, I have hereto affixed my signature.

GEORGE W. GOMBER.
